CAN END FEEDING MECHANISM.
APPLICATION FILED MAR. 20, 1919.

Patented Sept. 14, 1920.

2 SHEETS—SHEET 2.

UNITED STATES PATENT OFFICE.

WILLIAM CAMERON, OF CHICAGO, ILLINOIS, ASSIGNOR TO CAMERON CAN MACHINERY CO., OF CHICAGO, ILLINOIS, A CORPORATION OF ILLINOIS.

CAN-END-FEEDING MECHANISM.

1,352,578.

Specification of Letters Patent. Patented Sept. 14, 1920.

Application filed March 20, 1919. Serial No. 283,786.

To all whom it may concern:

Be it known that I, WILLIAM CAMERON, a citizen of the United States, residing at Chicago, in the county of Cook and State of Illinois, have invented certain new and useful Improvements in Can-End-Feeding Mechanism, of which the following is a specification.

This invention relates in general to feeding mechanism and has more particular reference to a mechanism for separating and feeding can ends which are adapted to be applied to the cylindrical bodies of tin cans. It will be observed, however, that the principle of my invention may be embodied in mechanisms for feeding other articles than tin can ends.

One of the primary objects of this invention is to provide a mechanism which will effectually separate the can ends or other articles in a magazine one from another and deliver them in succession one at a time from the magazine to a machine or other instrumentality adapted to act upon the delivered ends.

Another object of my invention is to provide a mechanism of this character which will be simple in construction and accurate in operation so that the delivery of a can end at regular predetermined intervals will be insured.

Further objects and many of the inherent advantages of my invention will be readily appreciated by those skilled in the art as the invention becomes better understood by reference to the following description when considered in connection with the accompanying drawings.

Referring to the drawings,—

40 Fig. 1 is a side elevation partially in section of a feeding mechanism embodying my invention.

Fig. 2 is a sectional view on the line 2—2 of Fig. 1.

45 Fig. 3 is an enlarged fragmentary view showing the driving release.

Fig. 4 is an end elevation looking toward the right at the structure shown in Fig. 1; and

50 Fig. 5 is an enlarged fragmentary view of the separating and feeding worm.

While my improved feeding mechanism may be employed as an independent unit or attached to any machine to which the articles delivered by the feeding mechanism are

to be supplied, I have, in the present instance, illustrated my invention as attached to a seaming machine adapted to apply can ends to previously formed cylindrical tin can bodies. On the drawings, reference character 6 indicates generally a portion of the frame of a seaming machine and 7 indicates a shaft of this machine upon which is mounted the rotatable head 8 provided upon its periphery with pockets 9 into which the can bodies are fed in succession from an inclined chute 11. All of this mechanism may be of well-known or preferred construction and only a fragmentary portion is illustrated, the mechanism by which the can ends are seamed onto the bodies 12 being omitted from the drawings.

Upon the frame of the seaming machine and at the end of the head 8 I have mounted a casting 13 which carries the can end magazine and the operating mechanism associated therewith. The casting 13 is provided near each end with laterally and upwardly extending arms 14 and 15, respectively, adapted to support the side members 16 which are preferably in the form of rods designed to serve as the side walls of the magazine. It will be observed that each rod is connected with its respective arms by bolts 17 extending through slots 18 in the arms 15 thereby providing for adjustment by means of which the distance between the side members may be regulated to accommodate can ends of different dimensions. The bottom of the magazine consists of a plate 19 carried by the casting 13 and the can ends 20 rest on edge on this plate and are guided and maintained in position in the magazine by the side members 16, as will be obvious from Figs. 1 and 2. The magazine is arranged on an incline, as shown, so that as the can ends are stacked in the magazine on edge they tend to feed by gravity toward the lower end thereof from whence they are delivered to the head 8 of the seaming machine, as will be later explained.

Immediately beneath the plate 19 there is rotatably mounted in suitable bearings formed in the casting 13, a shaft 21 equipped at its outer end with a bevel gear 22 adapted to mesh with and be driven by a companion bevel gear 23 carried by the upper end of the shaft 24. The shaft 21 is provided in proximity to the lower end of the magazine with a worm 25, the threads of which project

upwardly above the plane of the bottom plate 19 and are spaced apart just sufficiently to accommodate the edge of a single can end 20 so that as the worm revolves, it will separate at its upper end from the contiguous ends, that end which is engaged by the initial portion of the worm. Since the threads are designed to rather snugly engage the edges of the can ends it will be manifest 10 that they will be positively fed along by the worm in separated relation, substantially as illustrated in Figs. 1 and 5, to the delivery end of the worm where they will be successively discharged one at a time.

15 For the purpose of preventing the ends from tipping over or becoming displaced when they are released by the worm, I have provided each side member 16 of the magazine with an inwardly projecting abutment 20 or shoulder 26 disposed substantially above the delivery end of the worm. From Fig. 5 it will be observed that this shoulder is inclined rearwardly from top to bottom with respect to the worm, although as a matter of fact, the worm and magazine are inclined and this shoulder is disposed vertically. Movement of the can ends longitudinally of the magazine being limited by these abutments, when the lowermost end is delivered 30 by the worm, this end will drop edgewise under the influence of gravity into the underlying pocket 9 of the head 8 in proximity to the end of the can body 12, as shown in Fig. 1. A plate 27, disposed beneath the screw, serves to guide the discharged can end and to maintain it in position in the pocket 9. As the head 8 revolves the end is carried along with its body to the mechanism by which the end is attached to the 35 body and the next succeeding pocket with a can body therein will be brought into alignment with the magazine to receive the next end delivered by the worm.

The worm is driven in timed relation with 40 the head 8 through the shaft 24 which in turn is driven from the main drive shaft 28 of the seaming machine. A pair of bevel gears 29 and 31 provide the driving connection between the shafts 28 and 24, these 45 gears and also the gears 22 and 23 being preferably inclosed in casings 32 and 33, respectively, as a safety precaution.

In order that the can ends may not be jammed or distorted or that injury to the 50 mechanism may not result from undue strain imposed upon the worm by a jam or other unusual condition, I have provided a safety release in the driving mechanism which will permit the feeding mechanism to stop when 55 the strain thereon becomes excessive. This mechanism, best shown in Figs. 1 and 3, comprises a pair of plates or blocks 34 and 35 attached respectively to the hub of the gear 31 and to the shaft 28. The plate 34 is 60 provided on its face opposite to the block 35

with a radial groove or depression 36 and the block 35 is provided with a pin or bolt 37 normally urged outwardly to the position shown in Fig. 3 by an expansion spring 38, the outer end of the pin being tapered as 70 indicated at 39. It will be obvious that when the strain upon this driving connection becomes excessive the pin will be pushed backwardly against the force of the spring 38 so as to disconnect the shaft 28 from the gear 31. When the cause of the undue strain upon the feeding mechanism has been removed the connection will be automatically re-established and since this connection 75 can be re-established only in one relative position of the shaft 28 and gear 31, the worm will always be driven in predetermined 80 timed relation with respect to the head 8 so that a can end will be delivered at the proper instant to be received in the pocket 85 9. Since the shaft 28 is the main driving shaft of the seaming machine it will be manifest, of course, that the head 8 is also driven from this shaft, consequently the proper timed relation between the head and 90 the delivering worm is insured.

It is believed that my invention, its mode of operation and many of its attendant advantages will be understood from the foregoing without further description and while 95 I have shown and described a preferred embodiment of my invention it should be manifest that many variations in the size, shape, proportion and arrangement of the various parts may be resorted to without departing 100 from the essence of the invention as set forth in the following claims.

I claim:

1. In a can end feeding mechanism, the combination of a magazine including a bottom, a worm disposed longitudinally of the magazine parallel with said bottom and having threads spaced to accommodate the edge of one end only between successive threads, means for actuating said worm to separate 105 the ends in the magazine and feed them in separated relation toward the delivery end thereof, and an abutment disposed in the path of said can ends to insure an edgewise delivery of the ends from the magazine 110 when released by said worm.

2. In a can end feeding mechanism, the combination of an inclined magazine, including inclined arms and side members adjustably mounted thereon, a worm disposed 120 longitudinally of said magazine near the delivery end thereof, said worm having threads arranged to separate the can ends one from another and feed them in separated relation to the delivery end of the 125 magazine, and an abutment positioned in the path of the advancing ends above said worm.

3. In a can end feeding mechanism, the combination of a magazine including a bot- 130

tom plate and adjustable side members, means for separating and feeding the can ends in separated relation toward the delivery end of the magazine, and means for causing said ends to be delivered from the magazine transversely to the direction of movement in the magazine.

4. In a can end feeding mechanism, the combination of a magazine comprising an inclined bottom and side walls, means whereby said side walls may be adjusted to accommodate can ends of various dimensions, a feeding and separating worm having threads projecting above said bottom into the magazine near the delivery end thereof, and means for operating said worm to deliver said can ends one at a time from the magazine.

5. In a can end feeding mechanism, the

combination of an inclined magazine comprising adjustable side members, a feeding and separating worm disposed near the delivery end of said magazine, and means for operating said worm, comprising a releasable connection adapted to be released when excessive strain is imposed upon said driving mechanism.

6. In a can end feeding mechanism, the combination of an inclined magazine comprising a bottom plate, adjustable side members, a worm having its threads projecting into the magazine, an abutment in the path of the can ends above said worm, and means for driving said worm, including a connection adapted to be released when excessive strain is imposed upon said driving mechanism.

WILLIAM CAMERON.
